UNITED STATES PATENT OFFICE.

EDGAR O. KAUP, OF SEATTLE, WASHINGTON, ASSIGNOR TO WESTERN BLOWER COMPANY, OF SEATTLE, WASHINGTON, A CORPORATION OF WASHINGTON.

AIR WASHER.

Application filed December 3, 1923. Serial No. 678,197.

To all whom it may concern:

Be it known that I, EDGAR O. KAUP, a citizen of the United States, residing at Seattle, in the county of King and State of Washington, have invented certain new and useful Improvements in Air Washers, of which the following is a specification.

This invention relates to apparatus for use, more especially, with air-washers to remove free particles of liquid from washed air or other gases by means of eliminator plates.

The object of my invention, generally, is the perfecting of apparatus of this character to improve its efficiency, to enable it to be conveniently handled, transported, and adapt it to be readily and rapidly erected or repaired by unskilled labor at a minimum of expense.

A more specific object is to provide an air washer having assemblies of eliminator plates which are arranged to be removed in groups from the casing, and subsequently permitting the respective groups to be taken apart to allow the plates to be individually cleaned, painted or replaced by new ones.

Other specific objects and advantages of the invention will appear in the following specification.

The invention consists in the novel construction and combination of parts, and in the novel means for separably connecting the eliminator plates in a group or groups, and in the means for securing the assembled groups of plates within the casing therefor, as will be hereinafter described and claimed.

In the accompanying drawing,—

Figure 1 is a transverse sectional view taken on line 1—1 of Fig. 2 of an air washer embodying my invention. Fig. 2 is a longitudinal vertical section of Fig. 1, parts of the washer casing being broken away. Fig. 3 is a fragmentary horizontal sectional view on line 3—3 of Fig. 2. Fig. 4 is an end elevation of Fig. 3. Fig. 5 is a perspective view of one of the eliminator plate-spacing elements shown in the preceding views.

In said drawing the reference numeral 10 represents a casing open at both ends and formed with side walls 11 and a top wall 12 which are, by preference, separably connected together as by bolts or other known fastening means. Said casing is mounted upon a base member 13 in the nature of a liquid containing receptacle or tank.

As shown, there is provided within said casing a plurality of vertically disposed eliminator plates 14 preferably of corrugated shapes and arranged in side by side relations to afford intermediate the plates 60 tortuous passages, such as 15, Fig. 3, disposed in substantially parallel relations with the casing side walls 11. Each of said plates is preferably formed of a succession of plane portions, as 16, disposed in approximately the angular relations in which they are illustrated in Fig. 3.

According to the present invention, said plates are arranged in groups as *a*, *b*, *c*, and *d* in Fig. 1, for example. Said groups are 70 bodily removable from the casing and the plates themselves are removable from the respective groups as hereinafter explained.

More particularly each group of eliminator plates 14 have positioned between their 75 upper and lower ends spacing members 17 and 17¹ arranged in series located respectively adjacent to the front and rear faces of the plate assembly.

Each of said spacing members is preferably of a U-shape, and the upper spacing members 17 are employed in inverted positions, as illustrated in Figs. 1 and 2.

The plates of a group thereof are rigidly secured to each other and to the respective 85 series of spacing members by means of headed tie-bolts 18 extending through aligned holes provided in the plates and in the side flanges, as 19, Fig. 5, of the spacing members, and nuts 20 engaging screw threaded 90 ends of said bolts. 21 represent washers provided on said bolts to furnish seats for the bolt heads and nuts.

Some or all of the spacing members are provided in their web elements, as 22, with 95 holes as 23, to receive bolts 24 for removably securing a group of plates to the flanges 25 and 26 of bar elements 25¹ and 26¹ of the casing.

These bar elements are desirably of angle 100 bars, or an equivalent, and are spaced vertically apart to enable the groups of plates to be inserted therebetween.

If at any time it is desired to remove an eliminator plate for cleaning or renewing, 105 the unit or group of plates to which the plate belongs is taken from the casing after removing the respective bolts 24 and the unit itself is then disassembled by removing the bolts 18.

In operation, humidified air or other gas is driven or sucked through the passages 15 in an approximately horizontal direction, when the plates are arranged vertically as shown, the liquid laden air or gas thus travelling through the washer impinges against the angularly disposed surfaces of the eliminator plates resulting in the free liquid in the air or gas being condensed or 10 deposited upon the plates and from which the liquid drains into the tank.

While I have described the invention as applied to a vertical arrangement of eliminator plates, I do not wish to be understood 15 as confining the invention to such an arrangement, inasmuch as the plates often times may be advantageously employed in horizontal or oblique positions.

What I claim, is:—

20 1. In apparatus of the character described, the combination of a casing, provided interiorly with bar elements, a plurality of corrugated eliminator plates disposed between said bars, U-shaped members interposed be- 25 tween the adjacent plates for retaining the

latter in spaced relations with each other to afford tortuous passages between the adjacent corrugated plates, means extending through said plates and the spacing members for detachably connecting them together 30 as a unit, and fastening means engaging said spacing members and the respective casing bars for removably securing a unit within the casing.

2. In apparatus of the character described, 35 a casing provided interiorly with vertically-spaced bar elements, a unit comprising a plurality of vertically disposed eliminator plates, spacing members interposed between the upper and lower ends respectively of said 40 plates, and fastening means for engaging the plates and spacing members of the unit together, and means engaging in said spacing members and the casing bars for removably securing said unit within the casing.

Signed at Seattle, Washington, this 2nd day of November, 1923.

EDGAR O. KAUP.
